UNITED STATES PATENT OFFICE.

GEORGE LAWSON BALLARD, OF TORONTO, CANADA.

FUR-SEWING MACHINE.

No. 807,346.

Specification of Letters Patent.

Patented Dec. 12, 1905.

Application filed May 12, 1904. Serial No. 207,671.

To all whom it may concern:

Be it known that I, GEORGE LAWSON BALLARD, of the city of Toronto, in the county of York, in the Province of Ontario, Canada, have 5 invented certain new and useful Improvements in Fur-Sewing Machines, of which the following is a specification.

My invention relates to improvements in fur-sewing machines; and the primary object 10 of my invention is to reduce the weight and motion of the operating parts, so as to produce a light and smooth movement less liable to rattle the machine, and thereby consequently increase its durability; and further objects are 15 to make a self-contained machine in which all the operating parts will be adequately protected inside the casing, provide for the adjustability of the parts to accommodate them to wear and tear, and also to provide for the 20 utilization on the same machine of different sizes of needles and loopers according to the work it is designed to sew, to devise an improved means for driving the feed-wheels, and, in fact, to dispense with all springs in the 25 drive of the machine, and thereby produce a positive drive not liable to get out of order. To attain these objects I have constructed and arranged my machine in detail, as hereinafter more particularly explained.

30 Figure 1 is a perspective view of my improved machine, portion of the casing being broken away to exhibit the construction and arrangement of different portions of the operating mechanisms. Fig. 2 is a perspective 35 view of the machine from the opposite side to that shown in Fig. 1, the casing being also likewise broken away to exhibit the working parts. Fig. 3 is a vertical section through the casing, showing the construction and arrangement of the cams on the main driving-shaft. Fig. 4 is a vertical section at right angles to the section taken in Fig. 3. Fig. 5 is 40 a detail showing the looper and arm, together with the means for holding the looper in the arm. Fig. 6 is a detail of the thread-tension device. Fig. 7 is a sectional detail through the needle-holder. Fig. 8 is a detail of the crank on the main shaft from which the needle-bar derives its reciprocating movement. 45 Fig. 9 is a plan view of the invention with the cover removed, showing the position of the looper relative to the needle-bar.

In the drawings like letters and numerals

of reference indicate corresponding parts in each figure.

55

A is the main casing of the machine, which is substantially cylindrical in form and provided with a forwardly-extending hollow offset A' in the base.

B is the main driving-shaft, which is divided in the center, as indicated in Fig. 8, and is journaled in suitable bearings A^x, forming part of the casing A, and is provided with suitable driving-pulleys B'. A crank is formed on the shaft B between the collars C and C' (see Fig. 8) by means of the pin c, held in the collars by the set-screws c' and c''. A block c³ is loosely held on the pin between the collars C and C'.

D is the inner feeding-wheel, which has a corrugated rim d, as indicated. The feed-wheel D is located in front of the casing and is secured at the upper end of the arbor D', which extends through the front bearing A^x, forming part of the casing, and the front lower bearing A³, forming part of the hollow offset A' of the casing.

d⁴ is a collar secured on the arbor D', and d' is a threaded sleeve through which the arbor D' extends and which passes through a correspondingly-threaded orifice in the bearing A^x. The lower end of the sleeve d' is provided with a nut d² of any suitable form.

d³ is a lock-nut fitting on the threaded sleeve d' and designed to lock the sleeve in any position to which it may be adjusted by means of the nut-shaped end d².

It will now be readily seen that the feeding-wheel D may be readily vertically adjusted as the rim becomes worn.

90

E is the opposing feeding-wheel, which is secured in the end of the short arbor E' and clamped by means of the screw e, extending through the lugs e' in the end of the arm E'. The feeding-wheel E is provided with a corrugated raised rim corresponding to the rim d in the feeding-wheel D.

F is a plate provided with a groove f, designed to form a needle-way, such plate being secured to the feed-wheel E by the central screw f'.

The arm E' is bent, as shown, at the front end, and is otherwise curved and formed, as shown, being supported intermediate of its length on the arm G, secured on the end of the rock-shaft g, suitably journaled in the cas-

ing. The arm E^2 is supported at the rear end by an arm G' , pivotally supported on the stud g' , journaled at the back of the casing.

G^2 is an arm secured to the rock-shaft g within the casing and connected by a rod g^2 to a bell-crank lever G^3 , journaled between the lugs a at the back of the casing. The forward end of the rod g^2 is threaded and provided with the adjusting-nuts g^3 and a spiral spring g^4 , extending between such adjusting-nuts and the back of the casing and encircling the rod g^2 .

It will now be seen by depressing the outer end of the bell-crank lever G^3 the arm G will be moved forwardly, and thereby throw the feeding-wheel E away from the feeding-wheel D , so as to permit of the insertion of the work. The tension required for holding the feeding-wheel E against the feeding-wheel D is of course regulated by the nuts g^3 and spring g^4 , hereinbefore referred to.

At the lower end of the arbor D' and within the offset A' of the casing I secure the ratchet-wheel H , which is provided with a downwardly-extending hub h . Upon the hub h I journal a sleeve H' , held in position by a washer h' and screw h^2 . On this sleeve H' , I provide the radially-extending arms H^2 and H^3 . Upon the arm H^2 , I secure the spring-held push-pawl h^3 , and upon the frame I pivot the spring-held locking-pawl h^4 . Both pawls engage with the ratchet-wheel H , as indicated.

I is a lever provided with a central opening i , through which extends the stationary counter-shaft J . The lever I is provided with a forked upper end I' , within which is located the eccentric K , secured on the main shaft B . The inner end of the lever I is pivoted on a pin i' , secured on the rocker-arm J' .

j is a rod connected at one end to the pin i' and at the opposite end to a pin h^3 on the arm H^3 .

a' is a slot in the frame opposite and of substantially the same size as the slot i^2 in the lever I .

2 is a screw having located at one end the block 3 , which is designed to fit within the slot i^2 and being provided with a head 4 and thumb-nut or wheel 5 for clamping the screw 2 , and consequently the block 3 , in any desired position in the slot i^2 . The screw 2 and block 3 serve as a fulcrum for the lever I , and it will be seen that such fulcrum is readily adjustable.

55 The eccentric K as the shaft B is caused to revolve rocks the lever I on its adjustable fulcrum and imparts, through the rod j , the requisite movement to the arm H^2 and pawl h^3 , so as to give the requisite feed to the wheel D , and consequently to the fur passing through the wheels D and E . The rapidity of the feed is regulated, as hereinbefore described, by means of the adjustment of the screw 2 vertically.

I shall now describe the needle and the manner in which it is held and the means by which it is given its requisite movement.

L is the needle-bar, which is journaled in suitable bearings in the front and back of the casing, through both of which it extends.

l is a bracket secured to or forming part of the front end of the needle-bar, and l' is a straddle-bracket fitting over the lower front end of the bracket l . The lower end of the straddle-bracket l' is provided with a recess l^2 , and the front end of the bracket l is also provided with an oppositely-located recess l^3 , and between the recesses, which extend longitudinally in the brackets, is held the needle 6 , such needle being clamped in position by means of the set-screw 7 , extending through the top of the straddle-bracket l' and abutting the top of the depressed lower portion of the bracket l .

M is a depending fork secured to the needle-bar L by the set-screw m . The prongs of the fork M extend to each side of the block c^3 on the crank-pin c and hug such block closely. The bottom end of the fork extends into a guideway M' , secured to the shaft J . It will thus be seen that upon the rotation of the main shaft B the requisite reciprocating movement is imparted through the fork M to the needle-bar and the needle-bar is held from swinging in its movement, and thereby the lateral sway of the needle is prevented as it reciprocates over the feeding-wheels.

A^4 is a cover for the casing, which is hinged at the back and is provided with an upwardly-extending lug a^4 , carrying a thread-tension device a^5 . The front end of the cover is provided with an opening a^6 , located opposite the opening a^7 at the top of the casing.

8 is a spring-arm secured to the casing beneath the opening a^7 , and 9 is a pin provided with a head against which such spring-arm is designed to come in contact to produce a tension on the thread as the needle moves forward. The course of the thread 10 is indicated by dotted lines in Fig. 1.

N is the looper-arm, which is in curved form, as shown, and has a forward end provided with a toe n of a form which it is not necessary here to describe. The looper N in the working of my machine coacts with the needle, as is well known in machines of this class, and in so coacting the toe n must be given to form the loop in sewing a lateral, backward, and forward movement and substantially at the same time a reciprocating movement from front to back, as well as a downward movement over the feed-wheel D in proximity to the rim. In order to effect this movement, I carry the looper N in the socket end of a lever N' . The rear end of the looper extends through a sleeve n' , such sleeve being held in position in the lever by a set-screw n^2 . The lever has a lateral off-

set N^2 , and such offset abuts the upper end of the bell-crank O , being pivotally secured therein by the pin o . The bell-crank O is pivoted on a pin o' , having bearings in the frame, and has a rearwardly-projecting forked lower end which extends over an eccentric O' , secured on the shaft B . The rear end of the lever N' is connected by a link $9'$ to a bell-crank 10 , journaled on the counter-shaft J . The connection of the lever to the link is made by a pin 11 , having an eccentric-pin $11'$ located in the end of same. By unscrewing the clamping-screw connecting the lugs n^3 at the end of the lever and turning the pin 11 the desired adjustment may be given to regulate the amount of downward throw of the front end of the looper. The lever N' is so set that it inclines toward the vertical plane passing through the needle, and this is preferably so, as it enables the pointed end of the looper to fit more closely the inner contour of the rim of the feed-wheel D when the looper has reached the limit of its downward movement toward the feed-wheel. Such incline of the lever and looper also serves to facilitate the passage of the needle into the loop, which is an important desideratum.

The bell-crank 10 has a roller $10'$ pivoted at the rear end, which extends into a cam-groove $12'$ in the cam-wheel 12 , and it is this cam-groove which imparts the necessary vertical movement to the rear end of the lever N' , and consequently to the forward end or point of the looper.

The reciprocating movement of the looper N is imparted to it by the eccentric O' acting within the forked lower end of the bell-crank O , as hereinbefore described, thereby tilting the bell-crank, which is pivotally connected to the looper-holder N' .

In order to impart a lateral oscillating movement to the looper N , I provide the following simple mechanism. P is an arm pivoted on a stud p , held in the front of the casing. Q is a peripheral cam secured on the shaft B . p' is a roller pivoted on a pin p^2 , fixed in the upper end of the arm P and extending into the groove of the peripheral cam. R is a guideway formed on the upper end of the arm P . S is a rod having journaled on the lower end the rotatable ball-shaped roller s and having the upper end formed in the shape of a clamping-sleeve s' , through which the looper N extends and to which the sleeve s' is clamped by the clamping-screw s^3 , extending through the lugs s^3 , forming portion of the sleeve. The clamping-sleeve s' extends slightly over the sleeve n' , as indicated in Fig. 5, in order that should the looper be withdrawn the sleeve n' will support the clamping-sleeve in position, so that the looper may be inserted through the sleeve again. The cam-groove imparts an oscillating movement to the bottom of the rod S , and thus it will be seen a similar movement is imparted to the forward end or toe n of the

looper. As, however, the looper is imparted a reciprocating movement from front to rear, at the same time it will be seen that the guideway R serves to allow of the oscillating lateral movement being imparted at the same time that the reciprocating movement is imparted, as the roller during the oscillating movement will pass backwardly and forwardly within the guideway R . It will consequently be seen that the looper is given its reciprocating, lateral oscillating, and required vertical movement necessary for its proper coacting with the needle by the mechanism I have hereinbefore described.

It will be apparent from this description that on account of the cam and eccentric motions hereinbefore described for imparting the requisite movements vibration is reduced in my machine to a minimum, and consequently the wear and tear are minimized and the durability of the machine increased to a maximum.

What I claim as my invention is—

1. A fur-sewing machine, comprising an inner feed-wheel, an outer feed-wheel, a needle, means for giving the needle a longitudinal movement, a looper having a curved end and toe, means for giving said looper a reciprocating movement, means for giving the forward end of the looper a lateral oscillating movement, means for giving said end a rising-and-falling movement said means being independent of each other and means including an eccentric for regulating the rising-and-falling movement, substantially as described.

2. The combination with the looper and looper-holding lever, of a bell-crank journaled in the frame and pivotally connected to said lever, means for tilting the bell-crank so as to impart a reciprocating movement to the looper, a counter-shaft, an arm journaled thereon, a link connected at one end to the arm, a pin extending through the end of the looper-lever said pin having an eccentrically-arranged projection, said projection extending through the opposite end of the link, means for imparting a rocking movement to the arm and means for giving said lever a rocking movement.

3. The combination with the looper and the looper-holding lever suitably pivoted and means designed to impart a reciprocating movement to the looper means for giving the end of the looper an up-and-down movement, of a rod provided with a clamping sleeve-shaped upper end fitting within a notch in the looper-lever and through which the looper extends, an arm journaled on the stud within the frame and provided with a guideway, a ball-shaped roller journaled on the lower end of the rod and located in the guideway, a roller journaled on a pin on the arm and a peripheral cam secured on the main shaft and into which such roller extends as and for the purpose specified.

4. The combination with the looper and

looper-holding lever, means for reciprocating said looper, means for giving the end of said looper an up-and-down movement, a rod having a clamping-sleeve at its upper end, said 5 looper-lever having a recess near one end into which said sleeve is adapted to fit, an internal sleeve having one end extending into the recess over which the clamping-sleeve extends so as to hold said clamping-sleeve in position 10 to receive the looper and means for oscillating the rod, substantially as described.

5. The combination with the needle and needle-bar held in suitable bearings in the casing, of the main divided shaft journaled in the casing 15 and provided at the point of division with inner end disks a pin removably connected to said disks, a block journaled on said pin between the disks, a depending fork secured to the needle-bar and straddling the block on the

crank-pin and a guideway for the lower end 20 of the fork as and for the purpose specified.

6. The combination with the needle and needle-bar and looper-bar, of the main divided shaft journaled in the casing, disks mounted at the point of division of said shaft, a crank-pin connecting said disks, a block journaled on said pin, a depending fork secured to the needle-bar and straddling the block, one of said disks having a cam-groove therein, a bar having a portion engaging said groove and a 25 connection from said bar to the looper-bar for giving the end of the looper-bar a reciprocating movement.

GEORGE LAWSON BALLARD.
